UNITED STATES PATENT OFFICE

DUANE R. NEAL, OF DAYTON, OHIO, ASSIGNOR TO FRIGIDAIRE CORPORATION, OF DAYTON, OHIO, A CORPORATION OF DELAWARE

REFRIGERATING APPARATUS

Application filed February 28, 1929. Serial No. 343,498.

This invention relates to refrigerating apparatus and especially to the condenser and its relation to the other refrigerating apparatus.

5 An object of the invention is to provide an efficient condenser.

Another object of the invention is to provide efficient cooling means for the refrigerant.

10 Further objects and advantages of the present invention will be apparent from the following description, reference being had to the accompanying drawings, wherein a preferred form of the present invention is clearly shown.

In the drawings:

Fig. 1 is a cross-section through the lower part of a refrigerator cabinet;

20 Fig. 2 is a front view of the compressor, condenser and fan of Fig. 1;

Fig. 3 is a top elevation of the condenser disclosed in Figs. 1 and 2;

25 Fig. 4 is a cross-section on line 4—4 of Fig. 3; and

Fig. 5 is a cross-section on line 5—5 of Fig. 4.

It has heretofore been the practice generally to design a very high speed fan for cooling the condenser and compressor of refrigerating apparatus. It was thought necessary to provide a very powerful draft of air in order to efficiently cool the refrigerant.

30 This invention contemplates designing and placing the condenser so that the cooling currents may be efficiently utilized in cooling the condenser and compressor. The utilization of such cooling efficiency will result not only in replacing a large bulky condenser with a smaller one but will also allow a slow speed,

40 more quiet fan to be used in cooling the condenser and compressor. In Fig. 1 is disclosed a cross-section through the bottom of the cabinet 10 with its framework 11, outer side panels 12 and 13, inner side panels 14

45 and 15, a front panel 16 and a lower door composed of the outer panel 17, inner panel 18 and frame members 19. Across the bottom of the cabinet are the base frame members 20, resiliently supporting a platform 21

50 on which is preferably located the compres-

sor 22 having the pipe or conduit 23 connected to the condenser 24 which will be more particularly described hereafter. A pipe 25 leads to the receiver 26. From the receiver a pipe 27 leads to a cooling unit in another part of the cabinet preferably of the flooded float controlled type such as disclosed in the patent to R. G. Osborn 1,556,708, issued October 13, 1925. Conduit 28 returns the refrigerant to the compressor. The motor 29 runs the compressor through the medium of the motor pulley 30, belt 31 and compressor pulley 32 on the compressor shaft 34. As disclosed in Fig. 2 the compressor pulley preferably has fan blades 33 either integrally therewith or attached thereto for providing a cooling draft of air over the compressor and condenser. A fan 35 may be provided on the motor so that the cooling draft of air after passing over the condenser and compressor will be drawn back over the motor.

As disclosed in Figs. 3, 4 and 5 the condenser has a coupling member 36 connected at one of its ends. This coupling member has a passageway 37 leading to the entrance 75 of two tubes or conduits 38 and 39 connected to the passageway 37. Fins 40 preferably surround these two tubes. Both the inner tube 39 and the outer tube 38 form a horizontal U-shaped section having the two arms 80 41 and 43 and the base 42 of the U. At one end of the top of the U these two tubes are bent downward at 44 to form the next layer similarly U-shaped of the condenser. Any number of these U-shaped horizontal sections 85 or layers may be formed. For the apparatus disclosed, however, it is preferably at the point 45 to drop the tubes a considerable space to avoid the shaft 34 of the compressor and fan. Supports 46 of any convenient form 90 may be provided for the condenser. A coupling member 47 similar to the coupling member 36 is provided at the other end of the condenser or connection to the tube 25. When assembled the condenser is preferably placed 95 about the compressor in the position illustrated in Fig. 1 and then the compressor pulley and fan is secured to the shaft 34. An examination of Fig. 1 will disclose that the condenser has a plane portion directly 100

in the path of the breeze from the fan and that as this fan breeze passes through the condenser part of it will strike the compressor and from the compressor it will be reflected off to other portions of the condenser. 5 That portion of the breeze which does not strike the compressor will continue to cool the other portions of the condenser. The apparatus is thus designed that the condenser has portions continually in the path of the breeze from the fan. It will be noted that the fins on the condenser will aid in directing the breeze through the front portion of the condenser due to the fact that the plane of 10 the fins is at right angles to the plane of the fan. After the breeze strikes the compressor and is deflected off the fins on the sides 41 or 43 being substantially parallel to the plane of the fan will aid in catching the deflected currents of air and conducting them across 15 the tubes 39 and 38. The design of the condenser so efficiently utilizes the currents that a small condenser of this type can be used in place of the large bulky condenser of the 20 prior art. Furthermore as the currents of air are efficiently utilized it will not be necessary to provide a high speed fan. A low speed fan is more quiet in operation than a high speed fan of the same form is apt to be. 25 The two tubes or conduits 38 and 39 are preferably connected in parallel from the coupling 36 to the coupling 47.

It is not desired to limit the invention to the specific form and arrangement of the 30 apparatus as disclosed. For instance the number and arrangement of U-shaped sections may be varied. Furthermore the fan 33 may not be formed integrally with the compressor pulley, but may be separate 35 therefrom. Likewise the clearance at the point 45 for the compressor shaft 34 may be varied. By U-shaped is meant an element 40 having two portions at an angle or curvature to a third portion. The length of each portion 45 and its angle or curvature to the other portions is a matter of choice. It is not intended to limit the word "U-shaped" to the 50 symmetrical preferred form disclosed in the drawings.

55 While the form of embodiment of the invention as herein disclosed, constitutes a preferred form, it is to be understood that other forms might be adopted, all coming within the scope of the claims which follow.

55 What is claimed is as follows:

1. In refrigerating apparatus, a compressor, a fan spaced from said compressor, a substantially U-shaped condenser having the base of the U located between said fan and said compressor.
2. In refrigerating apparatus, a compressor, a fan spaced from said compressor, a substantially U-shaped condenser having the base of the U located between said fan and said compressor, and the other portions ex-

tending on opposite sides of the compressor.

3. A refrigerating apparatus comprising in combination, a compressor, a motor for operating said compressor, a fan carried by one of said elements, a substantially U-shaped condenser having a portion disposed on the same side of said element as said fan and extending in a plane parallel to said fan, the other portions of said condenser being disposed in a plane transverse to said first mentioned portion and extending along the sides of said fan carrying element so as to be in the path of air moved by said fan. 70

4. A refrigerating apparatus comprising in combination, a compressor, a motor for operating said compressor, a fan carried by one of said elements, a substantially U-shaped condenser having a portion disposed between the fan and said element and extending in a plane parallel to said fan, the other portions of said condenser being disposed in a plane transverse to said first mentioned portion and extending along the sides of said fan carrying element so as to be in the path of air moved by said fan. 80

5. A refrigerating apparatus comprising in combination, a compressor, a motor for operating said compressor, a fan carried by the compressor, a substantially U-shaped condenser having a portion disposed on the same side of said compressor as said fan and extending in a plane parallel to said fan, the other portions of said condenser being disposed in a plane transverse to said first mentioned portion and extending along the sides of said compressor so as to be in the path of air moved by said fan. 90

6. In refrigerating apparatus, a compressor, a fan spaced from said compressor, a substantially U-shaped condenser having one portion of the U located between said fan and said compressor. 105

In testimony whereof I hereto affix my signature.
